(57) **CLAIM**

The ornamental design for a prone positioning apparatus, as shown and described.

DESCRIPTION

FIG. 1 is an isometric view of a prone positioning apparatus in accordance with an embodiment of the invention;

FIG. 2 is a left side elevation view of the prone positioning apparatus of FIG. 1;

FIG. 3 is a right side elevation view of the prone positioning apparatus of FIG. 1;

FIG. 4 is a top plan view of the prone positioning apparatus of FIG. 1;

FIG. 5 is a bottom plan view of the prone positioning apparatus of FIG. 1;

FIG. 6 is a front end elevation view of the prone positioning apparatus of FIG. 1;

FIG. 7 is a back end elevation view of the prone positioning apparatus of FIG. 1; and,

FIG. 8 is another isometric view of the prone positioning apparatus of FIG. 1.
